(74) Attorney, Agent, or Firm—Fulwider Patton LLP

(57) **CLAIM**

The new ornamental design of a multi-position mechanic's creeper, as shown and described.

DESCRIPTION

FIG. 1 is a perspective view, depicting a multi-position mechanic's creeper of the present invention;

FIG. 2 is a perspective view, depicting the underside of the multi-position mechanic's creeper of FIG. 1;

FIG. 3 is a top view, depicting the multi-position mechanic's creeper of FIG. 1;

FIG. 4 is a side view, depicting the multi-position mechanic's creeper of FIG. 1;

FIG. 5 is a perspective view, depicting the multi-position mechanic's creeper of FIG. 1 in an inclined seating configuration; and,

FIG. 6 is a perspective view, depicting the multi-position mechanic's creeper of FIG. 1 in an upright seating configuration.

The broken line showing of wheels is included for the purpose of illustrating environmental structure and forms no part of the claimed design.

1 Claim, 5 Drawing SheetsFIG. 1

FIG. 3

FIG. 4

FIG. 5

FIG. 6
